(57) CLAIM

The ornamental design for a hairdryer as shown and described.

DESCRIPTION

1. Hairdryer
2. Hairdryer
- 1.1: Front
- 1.2: Back
- 1.3: Left
- 1.4: Right
- 1.5: Top
- 1.6: Bottom
- 1.7: Perspective
- 2.1: Front
- 2.2: Back
- 2.3: Left
- 2.4: Right
- 2.5: Top
- 2.6: Bottom
- 2.7: Perspective

The new designs are related to a hairdryer which is used for drying and/or styling hair; the design characteristic lies in the shape and the reproductions best showing the design characteristic are reproduction 1.7 (the perspective view) and 2.7 (the perspective view). The broken lines in the drawings depicting portions of the hairdryer are for illustrative purposes only and form no part of the claimed design.
